Des. 220,743
Patented May 18, 1971

220,743

GOGGLES

Theodore C. Neward, 2066 W. 11th St.,
Upland, Calif. 91786

Original design application Apr. 7, 1969, Ser. No. 16,604,
now Patent No. 218,547, dated Sept. 1, 1970. Divided
and this application Jan. 16, 1970, Ser. No. 20,958

Term of patent 14 years

Int. Cl. D2—03

U.S. Cl. D2—234

FIG. 1.

FIG. 2.

FIG. 3.

FIG. 1 is a front perspective view of goggles embodying my new design;

FIG. 2 is a bottom view of the goggles of FIG. 1; and

FIG. 3 is a side view of the goggles of FIG. 1.

The characteristics features of my design reside in the particular configuration of the transparent shield.

This is a division of design application No. D. 16,604, filed Apr. 7, 1969, now Design Pat. No. D. 218,547.

I claim:

The ornamental design for goggles, substantially as shown and described.
